Primary Examiner — John A Voytek(74) *Attorney, Agent, or Firm* — Workman Nydegger(57) **CLAIM**

The ornamental design for a fluid trap, as shown and described.

DESCRIPTION

FIG. 1 is a front perspective view of the fluid trap showing the new design;

FIG. 2 is a front elevational view of the fluid trap;

FIG. 3 is a back elevational view of the fluid trap;

FIG. 4 is a right side elevational view of the fluid trap;

FIG. 5 is a left side elevational view of the fluid trap;

FIG. 6 is a top plan view of the fluid trap;

FIG. 7 is a bottom plan view of the fluid trap; and,

FIG. 8 is a left side view of the filter trap in cross-section.

The broken lines shown in the Figures are for illustrating portions of the fluid trap that form no part of the claimed design.
